UNITED STATES PATENT OFFICE.

PETER A. ALTMAIER, OF HARRISBURG, PENNSYLVANIA, ASSIGNOR OF
ONE-HALF TO SAMUEL F. BARR, OF SAME PLACE.

SAFETY-LOCK FOR FIRE-ARMS.

SPECIFICATION forming part of Letters Patent No. 320,038, dated June 16, 1885.

Application filed March 24, 1885. (No model.)

To all whom it may concern:

Be it known that I, PETER A. ALTMAIER, a citizen of the United States, residing at Harrisburg, in the county of Dauphin and State of Pennsylvania, have invented certain new and useful Improvements in Automatic Safety-Locks for Fire-Arms; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has relation to automatic safety-locks for fire arms, and the object is to provide a device for locking the triggers, so as to render the gun inoperative at all times, except when the triggers are released by the action of the locking device; and to this end the novelty consists in the combination, with the main triggers, of a secondary or locking trigger adapted to engage said main triggers and render them inoperative at all times except when unlocked by the action of the secondary trigger, as will be hereinafter more fully described.

In the accompanying drawings the same letters of reference indicate the same parts of the invention.

Figure 1 is a side elevation of the stock of a double-barreled breech-loading shot-gun embodying my invention. Fig. 2 is a side elevation of the trigger-plate removed from the gun.

Fig. 3 is a top plan view of the same, and Fig. 4 is a detached view in perspective of the locking-lever.

A is the trigger-plate, and B the guard. C are the triggers. D is a lever pivoted to a projection, a, on the inside of the trigger-plate and extending forward so that its free bifurcated ends d d will come in contact with the extensions c c of the triggers C. E is a screw-stud passing through the hole d' in the lever D, and secured to the trigger-plate.

A. F is a spiral spring extending from under the head of the screw E down to the lever D,

and its object is to press the said lever downward against the trigger-plate, which is its 50 normal position. This keeps the ends d d in contact with the triggers and prevents their slightest movement. G is a stud secured to and extending downward from the lever D, passing through a hole in the trigger-plate 55 and also through one in trigger-guard, terminating in a curved finger-piece, H, located outside of the trigger-guard. The spiral spring F in pressing the lever D downward forces its ends d d against the extensions c c of the 60 triggers and in the line of their motion, so that while the lever is in this position it is impossible to operate them. If, however, the finger-piece H be pressed upward the ends d d are raised above and out of the path of the trigger-extensions c c, and of course, there being 65 no obstacle in the way, they may be readily pulled to fire the gun in the usual manner. The normal position of the lever D being that of a lock to the triggers, it follows that it is 70 impossible to fire the gun through accident or carelessness, and it can only be done by first pressing the finger-piece H upward and then pulling the trigger. The moment the hand is removed from the piece H the spring F re- 75 stores the lever D to its normal position, which action immediately locks the triggers and effectually prevents their being operated except as above stated.

Having thus described my invention, what I 80 claim as new and useful, and desire to secure by Letters Patent of the United States, is—

The combination, with the trigger of a fire-arm, of the locking-lever D, pivoted to the trigger-plate B, and provided with the projecting curved finger-piece H and the stud E, secured to the trigger-plate and having spiral spring F adapted to normally hold said lever in contact with and lock the triggers, as and for the purpose set forth.

In testimony whereof I affix my signature in presence of two witnesses.

PETER A. ALTMAIER.
